UNITED STATES PATENT OFFICE.

WILLIAM S. WITTEN, OF CHICAGO, ILLINOIS.

GATE LATCH.

Application filed May 16, 1921. Serial No. 470,205.

To all whom it may concern:

Be it known that I, WILLIAM S. WITTEN, a citizen of the United States, and a resident of Chicago, in the county of Cook and State 5 of Illinois, have invented certain new and useful Improvements in Gate Latches, of which the following is a specification, reference being had to the accompanying drawings.

10 My invention relates to latches of the type suitable for use on gates and in similar situations, and has for its object to provide an improved latch of simple and rugged construction so that it will be well adapted for 15 use in exposed places, and will be capable of withstanding rough usage; also one which will be self-latching without the use of springs, and which may be cheaply manufactured and easily installed without requiring accurate fitting. I accomplish this 20 object as illustrated in the drawings, and as hereinafter described. What I regard as new is set forth in the claims.

In the accompanying drawings.—

25 Fig. 1 is an elevation of part of a gate and gate post showing my improved latch mounted on the gate;

Fig. 2 is an enlarged detail being a cross section on line 2—2 of Fig. 1 showing the 30 gate post equipped with a keeper provided with two guide lips so that the gate may swing into engagement with the keeper from either direction;

Fig. 3 is a similar view with a modified 35 form of keeper and gate post;

Fig. 4 is a perspective view of the latch member of my improved latch;

Fig. 5 is a perspective view, partly broken 40 away of the bracket which supports the pivot of the latch-member; and

Fig. 6 is a similar view showing the bracket which supports and limits the movement of the latch bolt.

Referring to the drawings.—7 indicates a 45 gate and 8 the gate post. These parts are shown merely as being typical, and I wish it to be understood that my improved latch may be applied to any situation for which it is adapted. 9 indicates the shank of the 50 latch member, and 10 an operating arm therefor, which is integral with the upper end of the shank 9 and unites therewith at a pivot bearing 11, as shown in Fig. 4. It will be noted that the arm 10 extends at 55 an angle to the shank 9, the object of which as will hereinafter more clearly appear, is

to aid in holding the latch-bolt in its operative position by the action of gravity.

12 indicates a cross-head which is secured between its ends to the lower end of the 60 shank 9. In the illustration of Fig. 4 the left-hand end 13 of said cross-head constitutes a latch-bolt, while the right-hand end 14 thereof aids in causing the latch-bolt to move to its operative position. As will be 65 apparent from an inspection of Fig. 1, inasmuch as the arm 10 and portion 14 of the cross-head lie at the same side of the pivotal point of the latch member, they will both operate to cause the shank 9 to swing to 70 the left as viewed in said figure.

The pivot bearing 11 is mounted within a bracket 15, the upper portion of which is made tubular, or in the form of a sleeve, to receive said bearing, and is perforated to 75 receive a bolt 16 which passes through the bearing 11, through the tubular portion of the bracket 15, and into or through the gate. This bolt serves as a pivot about which the latch member swings. Below the tubular 80 portion 15 of the bracket it is provided with a lip 17 which is perforated to receive a bolt 18, shown in Fig. 1. By means of the bolts 16 and 18 the bracket 15 is securely 85 fastened to the gate.

The cross-head 12 swings within a frame or bracket 19 which comprises two side plates 20, 21, which are connected at two diagonally opposite corners by integral studs 22, 23, as shown in Figs. 1 and 6, the opposite corners of said plates being connected together and secured to the gate by bolts 24, 25, as shown in Fig. 1. The bolt 24 also serves as a stop which limits the outward movement of the latch bolt 13, as indicated in Fig. 1, and movement of the latch-bolt in the opposite direction is limited by the stud 22. The latch-bolt is arranged to swing freely between the side plates 20, 21, but said plates support it against lateral 100 strains, as any such strains will tend to twist the shank 9, whereupon the end portions 13, 14 of the cross-head will bear against and be supported by the opposite side plates.

105 It will be observed that the brackets 15 and 19 are entirely disconnected from each other, which arrangement is advantageous because it permits the bracket 19 to be adjusted independently of the bracket 15, and consequently makes easy the installation of the bolt in places where it might otherwise 110

be quite difficult to apply it. Also it makes it possible to adjust the extent to which the latch-bolt projects beyond the edge of the gate accurately without its being necessary to make any change in the position of the bracket 15. This construction is also advantageous since it realizes an important saving in the cost of manufacture, and makes the latch lighter in weight without loss in efficiency.

In the construction shown in Figs. 2 and 3, the gate 7 is shown as mounted on a gate post 26 by means of hinges 27, the latch being adapted to engage the gate post 8 which is provided with a socket 28 to receive it. Preferably a keeper plate 29 is fitted over this socket, and is provided with two inclined lips 30—31 at its opposite margins so that the latch-bolt will be automatically moved back out of operative position as the gate is being closed from either direction. In Fig. 3 I have shown a modified form of gate post 8^a which instead of being provided with the socket or recess 28 is cut away at one corner to provide an abutment 32 which is engaged by the gate when in its closed position. With this arrangement I employ a keeper plate 33 having a single lip 34, as the gate can open only in one direction. In the latter arrangement the latch-bolt does not engage the gate post 8^a, but engages a perforation 35 in the keeper plate.

From the foregoing description it will be seen that the above described latch normally assumes its operative position by gravity but may be swung out of operative position either by means of the arm 10, or by pulling outward on the end portion 14 of the latch bolt. It is also moved out of operative position by engagement of the operative portion 13 with the inclined portion of the keeper plate. As it has no springs or other delicate parts to get out of repair, the latch is very substantial and cannot easily be damaged.

What I claim as my invention and desire to secure by Letters Patent, is—

1. A latch comprising a latch member having a shank, an operating arm at the upper end thereof and integral therewith, a pivot bearing at the juncture of said shank and arm, a cross-head at the lower end of said shank, one end portion of said cross-head constituting a latch-bolt, a

bracket supporting said pivot bearing, and a frame having side plates between which said cross-head swings and by which it is supported against lateral strains.

2. A latch comprising a latch member having a shank, an operating arm at the upper end thereof and integral therewith, a pivot bearing at the juncture of said shank and arm, a cross-head at the lower end of said shank, one end portion of said cross-head constituting a latch-bolt, a bracket supporting said pivot bearing, and a frame having side plates between which said cross-head swings, and by which it is supported against lateral strains, said bracket and frame being separate from each other, whereby they may be independently adjusted.

3. A latch comprising a latch member having a shank, an operating arm at the upper end thereof and integral therewith, a pivot bearing at the juncture of said shank and arm, a cross-head at the lower end of said shank, one end portion of said cross-head constituting a latch-bolt, a bracket having a sleeve which embraces said pivot bearing, and a frame having side plates between which said cross-head swings and by which it is supported against lateral strains.

4. A latch comprising a latch member having a shank, an operating arm at the upper end thereof and integral therewith, a pivot bearing at the juncture of said shank and arm, a cross-head at the lower end of said shank, one end portion of said cross-head constituting a latch-bolt, a bracket supporting said pivot bearing, and a frame having side plates between which said cross-head swings and posts at two diagonally opposite corners thereof, said plate having bolt holes at the other two corners of said side plates), whereby said frame may be secured in position on a gate.

5. A latch comprising a latch member having a shank, an operating arm at the upper end thereof, a pivot bearing at the upper end of said shank, a cross-head at the lower end thereof, one end portion of said cross-head constituting a latch-bolt, a bracket supporting said pivot bearing, and a frame, separate from said bracket, for supporting said cross-head against lateral strains.

WILLIAM S. WITTEN.
